ULTRASONIC APPARATUS FOR DEVELOPING POLYMERIC PRINTING PLATES

Wesley W. Miller, Wyncote, Pa., Hugh T. Greenlee, Gates Mills, Ohio, and Charles D. Hagerty, Philadelphia, and Gerold Litschi, Lansdale, Pa., assignors, by mesne assignments, to W. R. Grace & Co., New York, N.Y., a corporation of Connecticut

Filed Jan. 7, 1969, Ser. No. 15,245

Term of patent 14 years

Int. Cl. D16—06

U.S. Cl. D61—1

FIG. 2

FIG. 3

FIG. 4

FIG. 1 is a perspective view of an ultrasonic apparatus for developing polymeric printing plates embodying our new design,

FIG. 2 is a front elevational view thereof,

FIG. 3 is a left-side elevational view thereof, and

FIG. 4 is a top elevational view thereof.

We claim:

The ornamental design for an ultrasonic apparatus for developing polymeric printing plates, as shown.
